George H. Albee.

UNITED STATES PATENT OFFICE.

GEORGE H. ALBEE, OF NEENAH, WISCONSIN.

PUMP FOR WELLS.

1,108,856.

Specification of Letters Patent. Patented Aug. 25, 1914.

Application filed August 14, 1913. Serial No. 784,738.

To all whom it may concern:

Be it known that I, GEORGE H. ALBEE, a citizen of the United States, residing at Neenah, in the county of Winnebago and State of Wisconsin, have invented a new and useful Pump for Wells, of which the following is a specification.

My invention relates to the usual well pump having a single cylinder with check and lift valves therein, which cylinder is placed below the platform of the well at such a distance in the colder parts of the country as will be below the frost line, which line may vary from 4 to 8 feet or 10 more, but in wells of more than about 30 feet in depth, it may with advantage be placed much lower than in the depth above stated. The cylinder contains one of each of the usual two valves and is connected with 15 the pump stand and suction pipe, so that upon any defect existing in either valve, the entire pump stand, cylinder and suction pipe of whatever length it may be, must be removed from the well in order to make the 20 needed repairs, and the object of this invention is, to avoid the removal of the pump stand and suction pipe for the purpose of making repairs or renewals to the valves, which I do by placing the cylinder containing the valves, with the delivery pipe and spout connected to it, in a part separate from the stand and suction pipe, the cylinder being connected with the suction pipe by means of a slip joint, and its delivery pipe 25 being connected with the pump stand with a single bolt, whereby, upon the removal of said bolt, the delivery pipe and cylinder, with its valves can be easily lifted from the well, without disturbing the stand and suction pipe, and without removing but a few 30 square inches in area of the platform which may again be replaced in position, after the required repairs have been made.

My invention is shown in the accompanying drawing, in which:

Figure 1 is an elevation of a pump with my improvement. Fig. 2 is a vertical section of the pump cylinder, with its slip joint connection with the suction pipe, one member of which joint is below and separate from the other. Fig. 3 is a side elevation of the lower end of the cylinder, with a modified construction of its slip joint, its lower member being shown

in section and separated from the other 55 member. Fig. 4 is a plan of the pump stand below the line *a*, *a*, of Fig. 1, and its flange showing the position of the cylinder delivery pipe, and its suction pipe supporting rods therein. Fig. 5 is a plan of the 60 suction pipe carrying arm and showing the position of the suction pipe supporting rods and the cylinder above the arm, with the whole within the pipe of a bored well, the pipe being in section. Fig. 6 is a plan of the 65 suction pipe carrying arm, with the suction pipe therein. Fig. 7 is an elevation of the lower end of a pump stand with the pump cylinder and suction carrying arm suspended from the pump flange by a single 70 rod. Fig. 8 is a plan of the suction pipe carrying arm for Fig. 7. Fig. 9 is a plan of an arm for connecting the delivery pipe to the pump stand.

Figs. 2, 3, 4, 5 and 6 are upon a larger 75 scale than the others.

Similar numerals and letters indicate like parts in the several views.

1, indicates the pump stand; 2, its bottom flange; 3, its handle carrying arm; 4, its 80 handle; 5, a plurality of rods suspended from the pump flange, adjusted to uniform lengths between the suction pipe carrying arm and pump flange, and held in position with nuts 6 and 7; 8, the suction pipe carrying arm in Figs. 1, 5 and 6; 8^a, the suction pipe carrying arm in Figs. 7 and 8; 5^a, the rod for supporting the suction pipe carrying arm in Fig. 7 between nuts 9 and 10; 11, the suction pipe; 12, the pump cylinder; 13 and 90 14, piston and check valves respectively; 15 and 15^a, one member of a slip joint in Figs. 2 and 3 respectively; 16 and 16^a, the other members thereof. The members 16 and 16^a, are provided with angular shaped collars or 95 nuts 16^b, by which to turn them, and their threaded ends 16^c, for being screwed into holes 17, in the arm 8 or 8^a.

18, is the delivery pipe; 19, indicates a connecting piece between the delivery pipe 100 and pump stand; 20, a hole through the piece 19, for receiving the delivery pipe; 21, a bolt for securing the delivery pipe to the pump stand. It should be observed that this bolt is the only part that requires removal for taking 105 up the cylinder, with its valves. A cap 22, is mounted upon the upper end of the delivery pipe, through which the valve rod 23, which

extends upward from the lift valve reciprocates, a link 24, connecting said rod with the pump handle, which connection of course has to be broken in taking up the cylinder.

5 The improvement consists as before remarked, in providing for the easy and quick removal of the cylinder and both of the valves by means of the uncoupling of the 10 valve rod from the pump handle and the removal of the bolt 21, the slip joints, either the one shown in Fig. 2, having the tapering members, or the one in Fig. 3, having the straight members, with a packing piece 15 25, between, permitting the cylinder to be separated from its connection with the suction pipe, when it can be lifted out and again as easily replaced and secured. For wells that are bored and piped the suction 20 pipe carrying arm, shown in Fig. 6 is required it being of such form and dimension as will be within the bore of such standard sized pipe as is used in piping the well, as is shown in Fig. 5, and in any well, it is 25 preferable, as two of the suspending rods 5 are just outside of the circumference of the cylinder, and assist it to be guided for the easy entrance of one of the slip joint members into the other.

30 26, are holes in flange 2 for fastening bolts; 27 is a platform.

Having described my invention, what I claim and desire to secure by Letters Patent, is,—

35 1. A pump consisting of a suitable pump stand having a flange at its lower end adapted to be secured to the platform of a well, a pump handle pivotally mounted upon the upper end of the stand, one or more rods 40 connected with said stand adapted for insertion into a well and to extend downward the required distance therein, a suction pipe holding arm connected with the lower end of each rod and extending at 45 right angles therefrom a short distance, a suction pipe inserted through and depending from said arm extension and adapted to be extended into the water of the well, a pump cylinder connected with said suction 50 pipe having a piston and check valve therein, a pipe extending upward from said cylinder above the pump stand flange to near the top of the stand, a delivery spout below the upper end of said pipe, a rod 55 connected with said piston valve and extending upward through said pipe and being connected with said pump handle, said cylinder at its lower end above said arm extension, having a slip joint connection 60 with the suction pipe aforesaid, and its upward extending delivery pipe being connected to the pump stand with a suitable connecting arm and a bolt, the construction being such, that by uncoupling its valve 65 rod from the pump handle and removing

said bolt, the delivery pipe, the cylinder and its valves can be lifted from its slip joint connection and removed from the well, without disturbing the position of the pump stand and suction pipe.

2. A pump consisting of a suitable pump stand having a flange at its lower end adapted to be secured to the platform of a well, a pump handle pivotally mounted upon the upper end of the stand, a plurality of rods 70 connected with said pump stand adapted for insertion into a well and to extend downward therein the required distance, a suction pipe holding arm connected with the lower end of each rod and extending at 75 right angles therefrom a short distance, a suction pipe inserted into and depending from said arm extension and adapted to extend into the water of the well, one member of a pipe slip joint connection inserted into 80 said arm extension and forming a continuation of said suction pipe, a pump cylinder having upon its lower end the other member of the aforesaid slip joint connection, connecting it with the suction pipe, and having 85 the usual piston and check valves therein, a pipe extending upward from the upper end of the cylinder above the pump stand flange to near the upper end of the pump stand, a delivery spout below the upper end 90 of said pipe, means for securing said pipe at a point above the delivery spout to the pump stand, a rod connected with said piston valve and extending upward through 95 said delivery pipe and being connected with 100 said pump handle, two of the aforesaid suction pipe arm supporting rods being spaced apart a less distance than the outside diameter of said cylinder and arranged in position for acting as guides in inserting one 105 member of said slip joint connection into the other after the suction pipe has been suspended in a well.

3. A pump consisting of a suitable pump stand having a flange at its lower end adapted to be secured to the platform of a well, a pump handle pivotally mounted upon the upper end of the stand, a plurality of rods 110 connected with said stand adapted for insertion into a well and to extend downward 115 therein the required distance, a suction pipe holding arm connected with the lower end of each rod and extending at right angles therefrom a short distance, a suction pipe inserted into and depending from said arm extension and adapted to extend into the water of the well, one member of a slip joint connection inserted into said arm extension and forming a continuation of said suction pipe, a pump cylinder having the 120 usual piston and check valves therein, and upon its lower end the other member of the aforesaid slip joint connection, connecting it with the suction pipe, a pipe extending upward from the upper end of the cylinder 125 130

to near the upper end of said stand, a delivery spout below said upper end, means for securing said pipe near its upper end to said pump stand, a rod connected with said 5 piston valve, and with the pump handle, and all of said suction pipe supporting rods, the suction pipe holding arm and pump

cylinder being arranged within the circle of the inside diameter of a standard gage pipe for bored and piped wells.
